UNITED STATES PATENT OFFICE.

OTTILIE BIRNBAUM, OF VIENNA, AUSTRIA-HUNGARY, ASSIGNOR TO WESTINGHOUSE LAMP COMPANY, A CORPORATION OF PENNSYLVANIA.

METALLIC-FILAMENT LAMP.

1,009,129.

Specification of Letters Patent. Patented Nov. 21, 1911.

Application filed November 8, 1910. Serial No. 591,298.

To all whom it may concern:

Be it known that I, OTTILIE BIRNBAUM, a subject of the Emperor of Austria-Hungary, and a resident of Vienna, Austria-Hungary, have invented a new and useful Improvement Relating to Metallic-Filament Lamps, of which the following is a specification.

This invention relates to metal filament electric lamps and has for its object to provide an improved lamp of this kind in which the leading-in wires and intermediate supports for the filaments are prevented from becoming overheated.

In metal filament lamps as usually made, the cross-section of the leading-in wires and intermediate supports to which the filaments are attached is sufficiently great to prevent their becoming overheated by the electric current passing through them. Nevertheless they are heated very considerably by conduction of heat from the glowing filaments themselves, so that the cross-section of the leading-in wires and intermediate supports must be made sufficiently great to allow for this factor also in order that they shall not be overheated. If the leading-in wires and intermediate supports are heated excessively there is a tendency for the vacuum in the lamp bulb to become impaired, and for the bulb to become blackened owing to disintegration of the material of which the leading-in wires and supports are made. If, however, leading-in wires of greater cross-section are employed difficulties occur when fusing the same into the glass stem of the lamp and in fact this operation in such a case can only be carried out by the exercise of special precautions. This applies particularly in the case of lamps intended to take a current exceeding one ampere.

The object of the present invention is achieved by diminishing the production of heat due to the passage of current through those portions of the filaments which are near to the leading-in wires and intermediate supports. The amount of heat produced by the current in these portions can be diminished by reducing the resistance, for instance, by increasing the effective cross-section of the end portions of the filament by branching the same, while the generation of heat in the end portions can be eliminated almost entirely by short-circuiting the end

portions of adjacent filaments so that almost the whole of the current flows from one filament to the next without traversing the end portions. There will of course be some conduction of heat through these end portions, but the action on the leading-in wires and intermediate supports will obviously not be so great as when the end portions themselves are also heated by the whole of the current. In both cases, however, the cross-section of the leading-in wires and intermediate supports can be made much smaller than has hitherto been possible.

In the accompanying drawings, Figures 1 and 2 represent diagrammatically two arrangements of the filaments in accordance with the present invention. The filaments are of course in fact arranged around the glass stem of the lamp, but for the purpose of simplicity are here shown developed in one plane.

Referring to Fig. 1 the end portions of the filament 1 which are connected to the leading-in wires 2 and intermediate supports 3 are provided with branches which form parallel paths for the current. In this particular case the filament is provided near each end with a kink or bend, and a loop 4 of conducting material connects this kink to the leading-in wires 2 or intermediate supports 3. These loops may conveniently consist of the same material as the filament itself. The branching of the filament can be carried out in any suitable manner in which the resistance of the end portions of the filament is reduced so that less heat is generated and consequently less heat is communicated to the leading-in wires and intermediate supports.

The generation of heat in the end portions of the filament can be almost entirely prevented by short-circuiting these end portions in the manner shown in Fig. 2. The filaments are formed of such a shape as shown in the drawing for example that they can be looped together near their ends so that part of the current passes directly from one filament to the next at the point of contact 5 without traversing the end portions of the filaments or the intermediate supports, with the result that these end portions are not heated to the temperature they would attain if they were traversed by the whole of the current. It will be obvious

that this looping together of the filaments can only take place as regards the intermediate supports, while for the leading-in wires the cross-section of the end portions 5 of the filament connected thereto must be increased by providing loops or branches as described above. The end portions of filaments adjacent to one another can obviously be caused to touch over their entire length, 10 in order to short-circuit these end portions.

The kink or bend in the filament to which the loops are attached or by means of which the filaments are looped together, is conveniently produced after the filaments have 15 been made. In the case of ductile filaments they can readily be bent by any suitable means, but in the case of sintered filaments the filaments are heated to a temperature at which they become pliable, whereupon the 20 kink is made and the filament allowed to cool.

What I claim is:—

1. In a metal filament electric lamp, the combination with the leading-in wires and 25 intermediate supports, of filaments provided with a kink near their points of attachment to said leading-in wires and intermediate supports, and loops of conducting material passing around said kink and attached to 30 the leading-in wires and intermediate supports respectively.

2. In a metal filament electric lamp the combination with the leading-in wires and intermediate supports of filaments attached 35 to said leading-in wires and intermediate supports, the end portions of said filaments being short-circuited at a point near their

points of attachment to the intermediate supports.

3. In a metal filament electric lamp the combination with the leading-in wires and intermediate supports of filaments attached to said leading-in wires and intermediate supports, the end portions of adjacent filaments being interlooped near their points of 45 attachment to their intermediate supports.

4. In a metal filament electric lamp the combination with the leading-in wires and intermediate supports of filaments attached to said leading-in wires and intermediate 50 supports, the filaments which are attached to said intermediate supports being provided with a kink in their end portions and interlooped at said kink.

5. In a metal filament electric lamp the combination with the leading-in wires and intermediate supports of filaments attached to said leading-in wires and intermediate supports, said filaments being provided with 55 a kink in their end portions, the filaments which are attached to the intermediate supports being interlooped at said kink and the filaments which are attached to the leading-in wires having loops of conducting material in contact with the kink and attached 55 to the leading-in wires.

In testimony whereof I have hereunto subscribed my name this 27th day of October 1910.

OTTILIE BIRNBAUM.
